UNITED STATES PATENT OFFICE.

GEORGE H. FRITZSCHE, OF BROOKLYN, NEW YORK.

KNOCKDOWN DISPLAY TOY.

Application filed July 11, 1923. Serial No. 650,904.

This invention relates to a knock-down display toy, and has for an object to provide such an article which may conveniently be shipped in flat, compact form, and be readily set up, for display, in order to represent a store or similar building for commercial activity.

Another object consists in providing such an article which is readily adapted to use as an effective advertising medium.

Another object consists in providing such an article which is exceedingly cheap to manufacture and yet durable when set up.

A further object consists in providing certain improvements in the form, construction and arrangement of the several parts, whereby the above named and other objects may be effectively attained.

A practical embodiment of the invention is represented in the accompanying drawings, in which

Fig. 1 represents a front elevation of the article set up.

Fig. 2 represents a top plan view of the same, partly broken away.

Fig. 3 represents an end elevation of the same.

Fig. 4 represents a section taken in the plane of the line IV—IV of Fig. 1, looking in the direction of the arrows.

Fig. 5 represents a section taken in the plane of the line V—V of Fig. 1, looking in the direction of the arrows.

The article, in general, includes parts forming the floor and walls of a store, together with counters, and a façade.

The main body portion, which is intended to form the walls of the store, is preferably composed of a single piece, bent to suitable form, as clearly shown in Fig. 2. It is denoted by 1, 2 and 3, the numeral 2 being applied to the part forming the rear wall, and the numerals 1 and 3 to the parts forming the side walls. It will be observed that these parts are folded into a form which flares forwardly, in order to give a clear view of the interior of the store, from the front.

The floor and front, or façade, of the store are preferably composed of a single piece that is cut and folded into the desired shape. This piece includes the parts marked 4, 5, 6, 7 and 8. The part 4 constitutes the upper portion of the store front, the parts 5 and 6 the side portions of the front, and the part 7 the lower or sill portion; while

the part 8, which is bent back from the part 7, forms the floor of the store and is shaped to correspond with the arrangement of the wall parts 1, 2, 3.

The portions 4, 5 and 6 are provided with suitable slits adapted to receive tongues 9, 10, 11, 12, formed on the front edges of the parts 1 and 3 of the main body portion, in order to hold the body portion and front in assembled position. The parts 1, 2 and 3 also have slits for receiving tongues 13, 14, 15, formed on the portion 8 which constitutes the floor. This interengagement of the various parts just named serves to unite the same with a rigidity that is entirely sufficient.

The corners formed at the meeting edges of the parts 1 and 2, and 2 and 3, respectively, have downward projections 16, 17, that serve as legs, and these legs are made of substantially the same height as the lower front portion 7, in order that the article may stand upright with the floor 8 level.

Located within the main portion 1, 2, 3 are suitable counters 18, 19, 20. Each of these counters is formed by stamping out a blank and folding the same to constitute the front, sides and top of the counter. Each of the counters marked 18 and 20, has only one side portion formed thereon, which side portion stands toward the front of the store; since, owing to the position of these counters, it is unnecessary to have any side portion at the rear end of these counters. The counter marked 19, on the other hand, is preferably provided with both sides.

These counters are held in position by providing their tops, fronts and sides with suitable tongues that are fitted to enter slits appropriately located in the walls 1, 2 and 3, and in the floor 8. In the case of the counters 18 and 20, the tongues projecting from the tops thereof are denoted by 21, 21, 22, 22. The tongues projecting from the fronts thereof are marked 23, 24, and those projecting from the sides thereof are indicated by 25, 26.

The tongues on the top of the counter 19 are shown at 27, 27; those on the sides at 28, 29, and that on the front at 30.

An awning is preferably arranged along the lower part of the portion 4. It has a front 31 and ends 32, 33. This awning is intended to be held in position by a series of tongues 34 that project from the rear edge of its front and enter corresponding slits in

the portion 4 of the façade, or front of the store; as well as by tongues 35, 36 that are formed on its ends 32, 33 and enter slits in the portion 4.

5 The side front portions 5 and 6 of the store have suitable receptacles or boxes, designed, for instance, for loaves of bread and packages of coffee. These are preferably arranged so as to be level with the sidewalk 10 and are located at each end of the lower front portion 7.

15 The box arranged in connection with the portion 5 has a front 37 and ends 38, 39. It is held in position by tongues 40, 41 which are formed on its ends and enter slits in the portion 5. The cover of this box is preferably formed separate from the remainder. It is denoted by 42 and has a pair of tongues 43 that enter slits in the portion 5, to hold 20 the cover in proper relationship with the remaining members of the box. Another tongue 44 projects from the front of the cover and is intended to enter a slit formed in the front 37 of the box and serve as a 25 means of locking the cover in closed position.

30 The box arranged in connection with the portion 6 is preferably formed so as to imitate a coffee carton or package. It has a front 45, ends 46, 47 and a cover 48. This box is held in position by tongues 49 and 50, which are formed on the sides 46, 47, and enter suitable slits in the portion 6. The cover 48 has a tongue 51 that is adapted to 35 enter a corresponding slit in the portion 6, in order to hold the cover closed; and the sides 46, 47 may have flaps 52, 53, at their upper edges, which are adapted to fold inwardly and form supports for the cover 48 40 when it is closed.

45 It will be clear that all the parts hereinabove described may readily be formed by stamping the same from sheet material, such as cardboard, and that this stamping operation may not only properly form and slit the parts, but it may also simultaneously print on the surfaces to be exposed, any such form of advertising or decoration as may be desired. The manner of folding and

assembling the parts will be apparent from the foregoing description.

50 The tops of the counters and floor of the store may have slits or holes formed therein at suitable places, in order to act as supporting means for figures representing customers 55 and for imitations of articles of merchandise supposed to be dispensed by the store.

55 It will be understood that various changes may be resorted to in the form, construction and arrangement of the several parts, without departing from the spirit and scope of my invention; and hence, I do not intend to be limited to the details herein shown and described except as they are included in the 60 claims.

65 What I claim is:

1. A knock-down display toy comprising, 70 separate front and back, the front containing an opening and having a member foldable rearwardly along the bottom of said opening to form a floor, and the back being foldable to form a rear wall and forwardly flaring side walls, said back being separably connectible to said front and floor members whereby all of the members are held in place. 75

80 2. A knock-down display toy comprising, a front and a back member, the front member containing an opening and having a portion cut from said opening and foldable rearwardly along the bottom thereof to form a floor, the back member being separate and foldable around the free edges of said floor to form a rear wall and forwardly flaring side walls, a member cut and folded to form a counter and a member cut and folded to 85 form an awning; said back member being removably secured to said front member and its floor portion, said counter being removably secured to said back member and the floor portion of said front member, and said awning being removably secured to said front member, all such connections being by means of flaps adapted to be received by suitably located slots and held therein.

90 95 In testimony, that I claim the foregoing as my invention, I have signed my name this 9th day of July, 1923.

GEORGE H. FRITZSCHE
